US00D702692S

(12) **United States Design Patent**
Gallagher et al.

(10) **Patent No.:** **US D702,692 S**
(45) **Date of Patent:** **** Apr. 15, 2014**

(54) **CARD FOR HOLDING A DIGITAL STORAGE MEDIUM**

(75) Inventors: **Timothy Gallagher**, Christchurch (NZ); **Kerry Jackson Tahawai Bird**, Maketu (NZ)

(73) Assignee: **Digital Hard Copy**, New York, NY (US)

(**) Term: **14 Years**

(21) Appl. No.: **29/407,204**

(22) Filed: **Nov. 23, 2011**

(51) **LOC (10) Cl.** **14-02**

(52) **U.S. Cl.**

USPC **D14/436**

CLAIM

We claim the ornamental design for a card for holding a digital storage medium, as shown and described.

DESCRIPTION

FIG. 1 is a bottom perspective view of a card for holding a digital storage medium showing the new design;

FIG. 2 is a top perspective view thereof;

FIG. 3 is a front elevational view thereof;

FIG. 4 is a rear elevational view thereof;

FIG. 5 is a side elevational view thereof;

FIG. 6 is another side elevational view thereof;

FIG. 7 is a top view thereof; and,

FIG. 8 is a bottom view thereof.

Broken lines and portions contained within broken lines, are not claimed.

1 Claim, 6 Drawing Sheets
